(57) **CLAIM**

The ornamental design for a vice as shown and described.

DESCRIPTION

FIG. 1 is a top, front and right side perspective view of a vice showing the new design;

FIG. 2 is a top, rear and left side perspective view thereof;

FIG. 3 is a top plan view thereof;

FIG. 4 is a left side elevational view thereof;

FIG. 5 is a bottom plan elevational thereof;

FIG. 6 is a right side elevational view thereof;

FIG. 7 is a rear elevational view thereof;

FIG. 8 is a front elevational view thereof;

FIG. 9 is a top, front and right side perspective view thereof, the broken lines indicating a possible environment only and forming no part of the claimed design; and,

FIG. 10 is a left side elevational view thereof, the broken lines indicating a possible environment only and forming no part of the claimed design.

The broken line showing of various elements in FIGS. 5 and 8 depict portions of the vice, and form no part of the claimed design.
